UNITED STATES PATENT OFFICE

147,958

DESIGN FOR AN ASH TRAY STAND

Luciano Capitani, Aliquippa, Pa.

Application May 21, 1946, Serial No. 129,966

Term of patent 14 years

(Cl. D85—2)

To all whom it may concern:

Be it known that I, Luciano Capitani, a citizen of the United States of America, residing at Aliquippa, in the county of Beaver and State of Pennsylvania, have invented a new, original, and ornamental Design for an Ash Tray Stand, of which the following is a specification, reference being had to the accompanying drawing, forming a part thereof, wherein

I claim:

The ornamental design for an ash tray stand, as shown.

LUCIANO CAPITANI.
